US00D419589S

United States Patent [19]

Crossgrove

[11] Patent Number: Des. 419,589

[45] Date of Patent: ** Jan. 25, 2000

[54] TYPE FONT

[75] Inventor: **Carl Crossgrove**, San Francisco, Calif.

[73] Assignee: **Adobe Systems Incorporated**, San Jose, Calif.

[**] Term: **14 Years**

[21] Appl. No.: **29/076,538**

[22] Filed: **Sep. 12, 1997**

[51] LOC (7) Cl. **18-03**

[52] U.S. Cl. **D18/24**

[58] Field of Search **D28/24-33**
